UNITED STATES PATENT OFFICE.

IRVING S. MERRELL, OF SYRACUSE, NEW YORK, ASSIGNOR TO MERRELL-SOULE COMPANY, OF SYRACUSE, NEW YORK, A CORPORATION OF NEW YORK.

CONDENSING APPARATUS.

1,356,082.

Specification of Letters Patent. Patented Oct. 19, 1920.

Application filed December 26, 1916. Serial No. 138,975.

To all whom it may concern:

Be it known that I, IRVING S. MERRELL, a citizen of the United States of America, and resident of Syracuse, in the county of Onondaga, in the State of New York, have invented new and useful Improvements in Condensing Apparatus, of which the following, taken in connection with the accompanying drawings, is a full, clear, and exact 10 description.

This invention relates to certain improvements in evaporating apparatus.

The objects of the invention are to provide means for readily and easily bringing 15 parts of the apparatus into assembled operative position combined with mechanism for suitably moving the parts of the apparatus so that the material may be removed therefrom and parts thereof readily cleaned and 20 repaired when that may become necessary.

In the drawings—

Figure 1 is a side elevation of the evaporating apparatus of this invention.

Fig. 2 is a vertical lateral cross section of 25 the same.

Fig. 3 is a vertical longitudinal cross section of the same.

Fig. 4 is a horizontal cross section through the evaporating chamber.

The liquid evaporating apparatus comprises a vertically arranged cylindrical chamber or heater —35— formed preferably of thin sheet metal, such as sheet tin, and in the particular construction shown, comprises 30 a plurality of, in this instance twelve, segmental sections —36— having their adjacent longitudinal edge portions flanged outwardly and in contact to form a substantially tight joint which may be made liquid-tight by solder or other well known means, such flanges held in contact and connected together by suitable reinforcing bars —37— and —38— positioned upon opposite sides of associated flanges and connected together 40 by bolts or rivets —39— extending through the flanges and the reinforcing bars upon opposite sides thereof.

The bottom of the heater, or container is likewise formed of sector sections —40— 50 corresponding to the sections —36— and having their adjacent edges flanged outwardly in like manner and fitted between the same reinforcing bars —37— and —38— to form a continuation of the joint between the 55 sections —36—. The respective ends of the

bars —37— and —38— are flanged at right angles to the main body of the bars and bolted to suitable castings —41— at the top and —42— at the bottom of the heater, and the sector sections —40— are preferably riveted to the casting —42— which is provided with a central projecting boss —43— internally and externally threaded for a purpose hereinafter described.

The exterior surface of the chamber or 65 heater —35— is provided with a plurality of horizontally disposed circumferential drip rings —44—, preferably having their edges fluted. The water which condensed upon the surface of the heater runs down 70 upon the drip rings and drops from their outer edges to the bottom of the chamber.

The upper edges of the segmental members —36— terminate adjacent the upper edge of the circular casting —41— and the casting —41— is provided with a stepped portion upon its inner upper portion, in which and between the casting —41— and the segments —36— a cylindrical plate-like member —45— is adapted to be seated, and 80 suitable rivets —46— extend through the casting, through the plate —45—, and through the segments —36— for securing the parts together, and, for the purpose of 85 making a substantially smooth even interior contour, the segments —36— are provided with frusto-conical countersunk portions adapted to be drawn into the openings in the plates —45— by the frusto-conical head upon the bolts or rivets —46—.

A ring member —49— of sufficient interior circumference is tightly fitted over the plate —45— and carries a cylindrical sheet metal section —50—. A series of rivets or bolts —51— having their ends countersunk in the member —45— to serve to connect these members together and the ring —49— is spaced a sufficient distance from the upper edge of the member —45— to form a liquid-receiving channel between the member —45— and the section —50—, and this channel is provided with a suitable outlet —52— and a discharge pipe —53— alined with the outlet and connected to the ring —49— and the section —50— by the rivets —51— and —54—.

The circular casting —41— carries below it a second angular casting —55— secured thereto by bolts —56— or otherwise, and the casting —55— in turn carries a cylindrical 110

- shell —57— surrounding the heater —35— and having a suitable closed bottom —58— provided with a central opening fitted over the boss —43— upon casting —42— and secured in place by means of lock nuts —59— to form a chamber —60— adapted to receive steam through pipes —61— for heating the wall comprising the chamber or heater —35—. The steam inlet pipes 10 —61— enter, and discharge steam, tangentially of the shell or jacket —57— so that the introduced steam rotates between the shell —57— and heater —35— whereby a substantially uniform temperature is maintained at all portions of the heater —35— and the "drips" falling from the drip rings are thrown out away from the surface of the heater —35— by centrifugal force.
- The bottom —58— is provided with a suitable outlet pipe —62— for condensation, operably connected thereto in any suitable well known manner. The outlet pipe —62— may, as shown, be U-shaped in form to constitute, or may embody, a trap in which the 20 water of condensation collects to prevent the escape of steam from the steam chamber, and this pipe is provided with a suitable air-vent —62'— through which air entering with the steam, through inlet —61— may escape.
- The interiorly threaded boss —43— is adapted to receive the exteriorly threaded pipe —21— for conveying the liquid to the heater —35—. Within the heater or chamber —35— is positioned a beater —63— comprising a vertically arranged central shaft —64— having its lower end journaled in a spider —65— supported on the segments —40— and the casting —42—, and its upper 30 end removably mounted in and keyed to a hub —66— provided with a suitable end thrust spring —67— for holding the shaft to its bearing in the spider —65—.
- The shaft —64— carries a pair of spaced 40 castings —68— and —69—, the casting —68— arranged adjacent the interior of the lower surface of the heater —35— and the casting —69— arranged in a plane adjacent the upper edge of the plate —45—.
- These castings —68— and —69— comprise a plurality of radially extending arms, the casting —69—, as best shown in Fig. 7, comprising six arms united at their outer ends by a ring, and the casting —68—, as 50 best shown in Fig. 9, comprising a central portion and twelve radiating arms. The casting —69— carries a plurality of upright bars —74— having their upper ends alternately secured to the outer ends of the arms —70— and to the ring —71— intermediate the arms —70— by means of downwardly projecting flanges —75— to which the bars may be secured by rivets, bolts or otherwise. The lower casting —68— carries a suitable circular plate —76— of

slightly less diameter than the interior of the heater —35— and having its circumference coinciding with the outer edge of the bars —74—.

Intermediate the casting —69— and the 70 plate —76— are positioned a plurality of horizontally disposed ring-shaped plates —77—. The distance between the plates may gradually increase from the bottom toward the top. These ring-shaped plates 75 —77—, as likewise the closed plate —76—, are provided with slots —78— at their outer edges for receiving the bars —74— so that the circumference of the plates corresponds with the outer edge of the bars.

The opening at the center of the disks —77— is of substantially greater diameter than the shaft —64— so as to leave considerable space for the passage of vapor, as hereinafter described.

Suitable posts, having their lower ends projecting through openings —80— in the ring —71 and secured therein by keys or otherwise, project upwardly from the upper side of a plate-like ring —77— secured to 90 casting —69— and to these posts a suitable deflecting hood —81— is secured, in any suitable manner, as by soldering, rivets, or otherwise, said hood spaced vertically a short distance from the upper surface of the 95 ring —77— and provided with a vertical flange rotating with the beater —63— and within a downwardly depending flanged portion —83— upon a disk —84— carried by a T-shaped ring —85— secured by screws 100 or otherwise to a ring-shaped casting —86— which latter is mounted within and secured to the section —50— by rivets or otherwise. A suitable groove is formed between the T-shaped member —85— and the casting 105 —86— for the reception of suitable packing for forming an air-tight joint between this portion and the cap —88— of a suitable vapor condensing apparatus —89— hereinafter described.

A suitable deflecting plate is mounted upon the shaft —64— intermediate the upper of the plates —77— and the coöperating flanges —82— and —83— and alined with the openings through the plates —77— and the discharge outlet through the flanges —82— and —83—.

The bearing —66— carries an oil or grease cup —91— adapted to collect oil or other foreign matter that may flow from 120 the packed joint —92— for the shaft —93— of which the bearing —66— is a part, and upon which shaft a suitable beveled gear —94— is mounted for coöperation with a second beveled gear —95— mounted upon 125 a shaft —96— journaled in a supporting frame hereinafter described, and carrying suitable pulleys —97— for driving the beater, and the lower edge of the cap —88— is provided with a suitable flanged ring. 130

shaped member —98— removably secured thereto and forming, in connection with the cap —88—, a channel —99— adapted to receive and collect the condensation on cap 5 —88— as well as oil or other foreign matter which may be thrown from the cup —91— by centrifugal force, and from this groove the oil or other matter may flow outwardly through the neck —100— into a cylindrical 10 chamber —101— containing a substantially diametrically disposed pipe —102— provided with a plurality of perforations —103— for discharging water into the chamber to condense the vapor which is 15 drawn through the neck —100—, thereby producing a high degree of vacuum in the apparatus, the pump serving to exhaust a certain amount of air from the apparatus and to form a seal for the water outlet 20 through the pipe —105—.

The upper portion of the chamber —101— is provided with an opening —106— allowing access to the chamber for cleaning and repair purposes, and a removable cap 25 —107— normally closes the opening.

A suitable framework is provided for supporting the entire apparatus in operable position, and for convenience in operation, cleaning and assemblage, the heater —35— 30 with its jacket or shell —57—, the beater —63— and parts carried thereby, and the member —50— and parts carried thereby, which parts may be termed the centrifugal evaporating apparatus, are, as a unit, vertically movable with respect to the rest of the apparatus, so that the ring —85— and casting —86— forming a part of the centrifugal evaporating apparatus, and rigidly connected to the chamber —35—, may be 35 brought into and removed from engagement 40 or pressing coaction with the cap —88— of the vapor condensing apparatus —89—, all of which remains stationary upon its support. To accomplish this result, the opposite sides of the shell —57— are provided 45 with trunnions —120— suitably mounted in bearing blocks —121—, which blocks are vertically slidable between upright grooved members —122— upon the inner sides of 50 spaced posts —123—, which posts, in this instance, are formed of channel or U-shaped metal bars of sufficient length to extend above the vapor condensing apparatus —89— and to carry a suitable cross frame 55 —124— disposed upon the vapor condensing apparatus and secured to the posts disposed upon opposite sides of the centrifugal evaporating apparatus by suitable bolts —125—, which frame in turn carries bear- 60 ings —126— for the shaft —93— carrying gear —94— and bearings —127— for the shaft —96— carrying the gear —95—.

The blocks —121— are supported by rods —128— vertically disposed between posts 65 —123— and having their lower ends thread-

ed and engaged with suitable internally threaded gears —129—, rotatably mounted upon castings —130—, secured to and between the posts —123— by means of rivets, bolts or otherwise. 70

The gears —129— are adapted to be rotated in unison by suitable gears —131— mounted upon a shaft —132— journaled in brackets —133— carried by castings —130—. The shaft —132— has operably 75 mounted upon it a gear —134— adapted to mesh with a relatively small gear —135— mounted upon the end of a shaft —136— journaled in a bracket —137— mounted upon one of the posts —123— and in a 80 bearing —138— mounted upon a brace —139— extending upwardly and inwardly from a base —140— to engage one of the posts —123— at a point adjacent the cap —88— of the vapor condensing apparatus 85 —89—. The corresponding one of the posts —123— upon the opposite side of the centrifugal evaporating apparatus is provided with a similar brace —139— rising from a similar base —140— and in like manner extending upwardly and inwardly to engage the post at a point adjacent the cap —88— of the vapor condenser —89—. These braces are connected at their base by a suitable transverse bar —141—. 95

The shaft —136— is provided with a suitable handle —142— for rotating the same, thereby in turn rotating the shaft —132—, the gears —131— and thereby the coacting gears —129— for simultaneously 100 raising or lowering, as desired, the blocks —121— to raise and lower that portion of the apparatus, which may be termed the centrifugal evaporating portion, into engagement or pressing coaction with the cap —88— of the vapor condenser —89—. 105

A suitable framework is provided for supporting the chamber —101— of the vapor condensing apparatus, one side of which framework is shown in Fig. 3, the framework upon the opposite side being identical therewith, and comprises a suitable vertical post —143— carrying, in connection with post —123—, longitudinal bars —144—, and suitable obliquely disposed brace bars —145— extend from posts —123— to the post —143—. The chamber —101— is provided with suitable brackets —146— and which engage the upper longitudinal bar —144— and are secured thereto by bolts, as shown, or otherwise. The opposite side of the chamber —100— from that shown in Fig. 3 is provided with similar brackets supported upon a similar structure. 110 115

When the centrifugal evaporating apparatus is moved downwardly to such an extent that the casting —86— and ring —85— of the apparatus are disengaged with the cap —88— and the shaft —64— of the beater is withdrawn from the bearing 120 125 130

—66—, suitable mechanism is provided for tilting the centrifugal evaporating apparatus upon its trunnions —120— to permit removal of the beater from the chamber 5 —35—. This mechanism comprises, as best shown in Figs. 3 and 4, suitable bars —146— each having one end connected to the member —50— of the centrifugal evaporating apparatus, upon substantially diametrically disposed points, and having their opposite end portions bent at substantially right angles to the body of the bar and provided with threaded openings for receiving threaded shafts —147— suitably journaled 10 upon brackets —148— carried by the brace bar —145— and its corresponding member upon the opposite side of the apparatus, respectively.

These shafts are rigidly connected at their 20 ends to suitable beveled gears —149— meshing with other suitable beveled gears —150— mounted upon a shaft —151— carried by the brackets —148— and upon which shaft a suitable sprocket —152— is mounted, operably connected by chain or otherwise to a second sprocket —153— mounted upon a shaft —154— journaled in a bearing —155— operably carried by a post —123—. The sprocket —153— is adapted to be rotated by 25 a suitable handle —156— for transferring rotary movement to the sprocket —152—, the gears —149— and —150— for turning the shafts —147— thereby longitudinally moving the bars —146— as desired, either 30 to tilt the apparatus from vertical position or to return the same to vertical position 35 after tilting.

The mechanism described constitutes means for raising the heater or container 40 portion of the apparatus toward and from the stationary cap 88 forming an elbow connection between the liquid evaporating

chamber and the vapor condensing apparatus. In addition the mechanism constitutes a means for tilting or moving the liquid evaporating chamber about its supporting pivots to permit removal of the interior parts for cleaning of the same. Modifications may be made in the details of construction without departing from the invention 50 as set forth in the appended claims. 45

What I claim is:—

1. In an evaporating apparatus, a framework, a liquid evaporating chamber and a cap therefor, both carried by said framework, one of said elements being movable on the framework toward and from the other, a rotary beater within the liquid evaporating chamber and a sectional shaft for driving said beater, said shaft separable 60 into said sections when the movable element is moved away from the coöperating element. 55

2. In an evaporating apparatus, a framework, a liquid evaporating chamber and a cap therefor, both carried by said framework, one of said elements being movable on the framework toward and from the other, a rotary beater within the liquid evaporating chamber and a sectional shaft 70 for driving said beater, said shaft separable into said sections when the movable element is moved away from the coöperating element, and interlocking parts on said sections engaged to effect rotation of the sections when the movable element is brought 75 into contact with the co-acting element.

In witness whereof I have hereunto set my hand this 27th day of November, 1916.

IRVING S. MERRELL.
